UNITED STATES PATENT OFFICE.

JOHN T. VOLLM, OF ROCHESTER, NEW YORK.

ARCH-SUPPORTING SHOE.

Application filed January 16, 1922. Serial No. 529,492.

My present invention relates to shoes and, more particularly, to shoes especially equipped to give support to the arch of the foot in cases where the wearer's arches are 5 weak, and the invention has for its object to provide a simple, cheap and convenient means for adjusting the arch supporting portion of the shoe so that the device may be manipulated by unskilled persons effectively and conveniently. The improvements are directed in part to structural features wherein the arch and shank mechanism is built into the shoe structure to the advantage of both, and to these and other ends, the invention consists in certain improvements and combinations of parts, all as will be hereinafter more fully described, the novel features being pointed out in the claims at the end of the specification.

20 In the drawings;

Figure 1 is a fragmentary side view of a shoe partly broken away and partly in longitudinal section showing arch supporting means constructed in accordance with and 25 illustrating one embodiment of my invention;

Figure 2 is a similar view showing the arch support adjusted to a different position;

Figure 3 is a transverse section on the 30 line 3—3 of Figure 1;

Figure 4 is a top view of the adjustable arch supporting member and the adjacent element to which it is secured;

Figure 5 is a view corresponding to Figure 35 1 showing a modified embodiment of the invention;

Figure 6 is a top view of the arch supporting element of the modification;

Figure 7 is a section on the line 7—7 of 40 Figure 5, and

Figure 8 is an enlarged detail sectional view taken through the axis of one of the adjusting screws.

Similar reference numerals throughout 45 the several views indicate the same parts.

Referring first more particularly to Figures 1 and 3, I have illustrated my improvements applied to a woman's shoe of the usual construction embodying an outsole 1, 50 an insole 2 and an upper 3 all welted together as indicated generally at 4. In the practice of my invention, I prefer to split the rearward or heel portion of the insole to the point just forward of the arch, as shown 55 in Figure 1, dividing such portion into an upper ply 5 and a lower ply 6. On the under

side of the lower ply I arrange a steel stiffening shank 7 of any suitable or preferred construction to perform the general functions of the shank. It is secured to the insole at its forward end by a split rivet 8 extending all the way through and having its head on the upper side of the under ply while the rear end of the shank is tacked to said ply as shown at 9. Below the shank 7, and between it and the arch of the outsole 1 is a filler shank 10 that may be of paper, fiber or leather of suitable thickness to give the desired curvature. This filler shank may be cemented to the outsole, and is provided 70 with a central cavity 11.

The arch supporting member 12 is preferably a thin steel plate of substantially the form shown in Figure 4, the inner edge thereof being serrated at 13 to allow it to 75 bend uniformly and prevent a harsh contact with the instep. The front end is partially bifurcated by a notch 14 slidably straddling the rivet 8 and fitting under the head thereof, while the rear end is slotted at 15 to slidably receive a split rivet 16 by means of which it is secured to the under ply 6 of the insole and beneath the head of which rivet the rear end of the support is adapted to slide. Centrally the supporting plate 12 is pierced by an opening 17 to receive the head of an adjusting screw 18 that may be turned from the inside of the shoe, and to render it readily accessible the upper ply 5 of the insole is provided with a flap 19 that may be 90 raised to reveal the screw head.

This screw 18 is threaded into a nut or bushing 20 secured in the central portion of the stiffening shank 7 and which occupies the cavity 11 in the filler shank 10 without 95 interfering with the outsole 1, being entirely above the same, although the outsole in the region of the arch of the shoe is preferably given the conformation shown in Figure 3 to accommodate the structure above described. The screw 18 has a shoulder 21 just below its head which bears against the under side of the supporting plate 12. 100

The operation of the device is as follows: When the parts are in the normal position 105 of Figure 1, the arch support has only a gentle curve such as is common to the ordinary shoe. If the wearer finds that she requires more support for the arch of her foot the screw 18 is turned from inside the shoe 110 to the left which unscrews it from the fixed bushing 20 and forces the center of the arch

supporting plate 12 upwardly the required distance to increase the curvature of the plate and make the desired contact with the arch of the foot. This, of course, is against the natural spring tension of the plate 12 which is prevented from rising at its end by the heads of the rivets 8 and 16 yet the plate may slide on these rivets as is necessary to permit the upward bowing of the central portion. To lower the arch the screw is turned in the reverse direction and the plate 12 follows it downwardly because of its own tension. An arch support constructed in accordance with this invention does not mar the exterior appearance of the shoe, and yet is quite accessible for adjustment, and on the inside the upper ply 5 of the split insole covers any possible irregularities and gives the same appearance as that of an ordinary shoe.

In the modification shown in Figures 5 to 8 the general structure is the same except that three of the screws 18 are used as shown at 18^a, 18^b, and 18^c, so that the bow of the arch supporting plate 12^a may be regulated at several points throughout its length with greater nicety thereby not only the height of the arch may be regulated but its curvature as well. Three bushings 20^a, 20^b, and 20^c are of course used, and in this embodiment I have shown the arch plate 12^a secured between two shoulders 21^a and 22^a on the screw 18^a, the latter being formed by the head of the screw. For this purpose the plate 12^a is provided with key hole slots 23 to permit the plate to be applied to the screw heads. As the heads of the screws thus rise above the top face of the plate 12^a, I provide a leather spacing strip 24 on the upper side of the plate against the upper ply of the insole that is perforated to receive

the screw head and fills in the space. Also a liner is shown at 24^a above the insole.

I claim as my invention:

1. In an arch support for shoes, the combination with a two part insole, of a stiffening shank on the under side of the lower part, an adjustable arch supporting member between the parts, and adjusting means for the arch support arranged to react against the stiffening shank. 45

2. In an arch support for shoes, the combination with a two-part insole, of a stiffening shank on the under side of the lower part, an adjustable arch supporting member 55 between the parts, means extending through the lower part to slidably interlock the arch support and stiffening shank, and adjusting means for the arch support arranged to react against the stiffening shank. 60

3. The combination with a shoe embodying an outsole, an insole and an upper welted together, of a stiffening shank between the soles provided with a threaded bushing, a 65 filler shank between the stiffening shank and outsole and provided with a cavity for the bushing, an adjustable bowed arch support associated with the insole, and a screw threaded in the bushing to act against the arch support and accessible for operation 70 from the inside of the shoe. 75

4. The combination with a shoe embodying an outsole, an insole and an upper welted together, the insole being split at its heel portion to form upper and lower plies, of a 75 stiffening shank between the insole and outsole, an adjustable bowed arch support arranged between the plies of the insole, and means accessible for operation through one of the soles for regulating the arch support.

JOHN T. VOLL.
